UNITED STATES PATENT OFFICE.

ROBERT C. FARTHING, OF PADUCAH, KENTUCKY.

CYLINDER-BORING MACHINE.

Application filed August 23, 1923. Serial No. 658,993.

To all whom it may concern:

Be it known that I, ROBERT C. FARTHING, a citizen of the United States, residing at Paducah, in the county of McCracken and 5 State of Kentucky, have invented certain new and useful Improvements in Cylinder-Boring Machines; and I do hereby declare the following to be a full, clear, and exact description of the invention, such as will 10 enable others skilled in the art to which it appertains to make and use the same.

The object of the present invention is the provision of a machine for boring and truing cylinders and the like, and which is 15 simple, effective and readily operable.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to 25 without departing from the nature of the invention.

Referring to the accompanying drawings forming a part of the application:

Figure 1 is a side elevation of a boring 30 machine embodying the invention,

Figure 2 is a sectional detail on an enlarged scale, parts being broken away,

Figure 3 is a horizontal section on the line 3—3 of Figure 1,

Figure 4 is a horizontal section on the line 4—4 of Figure 1,

Figure 5 is a detail view of the tool holder,

Figure 6 is a vertical sectional view of 40 the tool holder and a portion of the boring shaft, and

Figure 7 is a horizontal section on the line 7—7 of Figure 6.

Corresponding and like parts are referred 45 to in the following description and designated in the several views of the drawings by like reference characters.

The numeral 1 designates a post or standard provided with a base 2, whereby 50 it may be bolted or otherwise secured to a suitable support. The upper end of the post or standard 1 curves laterally, as indicated at 3, and terminates in a vertical sleeve 4. Brackets 5 and 6 are disposed 55 upon opposite sides of the post 1. A shaft 7 is mounted in the bracket 6 and post 1

and is provided at one end with a bevel pinion 8 which is in mesh with a bevel gear wheel 9 mounted in the bracket 5. The shaft 7 is provided with a crank 10 and a 60 stepped pulley 11. The crank 10 provides for manual operation of the machine and the stepped pulley 11 enables the machine to be operated from a suitable source of power in a manner well understood. 65

A boring shaft 12 has a snug fit within the bevel gear wheel 9 and is rotatable therewith by means of a feather or spline connection. The upper portion of the boring shaft 12 is reduced and externally screw 70 threaded, as indicated at 15, and cooperates with a feed nut 14 mounted in the sleeve 4, whereby to control the feed of the boring tool. A combined retainer and guide bracket 15 is secured to the post 1 75 above the gear wheel 9 and engages the latter and prevents vertical displacement thereof. The boring shaft 12 passes through the bracket 15.

A guide bracket 16 is secured to the post 1 80 and receives the lower end of the boring shaft 12 and steadies the same. A work table 17 is bolted or otherwise attached to the post 1 and receives and supports the cylinder or other part to be bored. Suitable 85 clamps 18 are provided upon the work table 17 to engage and hold the cylinder 19 or like part to be bored.

A centering block 20 is mounted upon the boring shaft 12 and serves to center the 90 work 19. The centering block 20 is of tapering form to adapt itself to the bore or opening of the cylinder 19 or like part.

A countershaft 21 is mounted in bearings at one side of the post 1 and is provided 95 with a stepped pulley 22 and tight and loose pulleys 23. The drive belt, not shown, cooperates with the pulleys 23 in a manner well understood and the stepped pulleys 11 and 22 provide for changing the speed of 100 the boring shaft. Obviously the machine may be operated by hand or power as required.

The numeral 24 designates the body of the tool holder, the same snugly fitting upon 105 the boring shaft 12 and held thereon by means of set screws 25 and 26, the latter also serving as means for adjusting the bit 27. A loop 28 forming a part of the tool holder and disposed relatively at the front 110 side thereof, receives the bit or cutting tool 27 which is held in the required adjusted

position by means of a set screw 29. The set screw 26 passes through a portion of the tool holder and a transverse opening of the boring shaft 12 and is disposed in line with the 5 bit or tool 27 and engages the inner end thereof and serves as means for adjusting the tool as required. When adjusting the tool 27, the set screw 29 is loosened, and when adjusted, the tool is made secure by tightening the set screw 29.

In practice, the cylinder 19, or like part to be bored or made true, is placed upon the work table 17 and is centered by means of the block 20, after which the clamps 18 are 15 tightened to secure the work and prevent possible displacement thereof. The boring shaft 12 is adjusted vertically to bring the cutting tool 27 to a position at the top of the cylinder 19 and said cutting tool is adjusted to remove a shaving from the inner 20 wall of the cylinder when the boring shaft 12 is rotated and lowered to advance the tool as the boring progresses. After the parts have been properly adjusted, the shaft 25 7 is rotated and imparts a corresponding rotary movement to the boring shaft 12, the latter being lowered to feed the cutting tool by means of the nut 14 which is manipulated by hand. The boring shaft 12 is supported 30 against lateral displacement by means of the bracket 16, sleeve 4, gear wheel 9 and bracket 15. The boring is true and may be accurately adjusted by means of the set screw 26 in the manner stated.

What is claimed is:

1. A boring tool of the character specified including a boring shaft, a tool holder including a sleeve mounted upon the boring shaft, and a set screw mounted in the sleeve and passing through the shaft for securing the tool holder to the shaft and also operating to adjust the tool. 40

2. A boring tool of the character specified including a boring shaft, a tool holder thereon, means carried by the tool holder 45 for securing the tool in the required adjusted position, and a set screw passing through a portion of the tool holder and through the shaft for securing the tool holder to the shaft and serving as adjusting 50 means for the tool.

3. A boring tool of the character specified comprising a boring shaft, a tool holder mounted upon the boring shaft and provided with a tool receiving loop, a set screw 55 for securing the tool in the required adjusted position, a second set screw for securing the tool holder to the shaft, and a third set screw passing through a portion of the tool holder and through the shaft and 60 adapted to engage the tool to effect adjustment thereof.

In testimony whereof I affix my signature in presence of two witnesses.

ROBERT C. FARTHING.

Witnesses:

I. N. ROGEN,
M. I. JORDAN.
